UNITED STATES PATENT OFFICE.

ROBERT P. SCHILLING, OF BERKLEY, VIRGINIA.

COIN-CONTROLLED VENDING-MACHINE.

SPECIFICATION forming part of Letters Patent No. 653,488, dated July 10, 1900.

Application filed February 19, 1900. Serial No. 5,808. (No model.)

To all whom it may concern:

Be it known that I, ROBERT P. SCHILLING, a citizen of the United States, residing at Berkley, in the county of Norfolk and State of Virginia, have invented certain new and useful Improvements in Coin-Controlled Vending-Machines, of which the following is a specification, reference being had therein to the accompanying drawings.

10 The invention relates to coin-controlled vending-machines, and has particular reference to a device of this character designed and adapted to dispense liquids.

15 The invention consists in the peculiar construction of the vending-machine and in the novel combination and arrangement of its various parts, as will be more fully hereinafter described and shown.

20 In the drawings, Figure 1 is a vertical central section, partly in elevation, through the machine detached from the casing. Fig. 2 is a side elevation, partly in section, of the mechanism, showing fragments of the casing attached thereto. Fig. 3 is a cross-section taken 25 on line xx , Fig. 2. Fig. 4 is a side elevation of the machine as in use. Fig. 5 is a vertical central section through the measuring-cup. Fig. 6 is a perspective view of the coin-actuating mechanism and the operating device 30 therefor; and Fig. 7 is a section on line yy , Fig. 3.

A' is an inclosing casing having an entering-slot B' formed therein, as shown.

35 A designates a receptacle within the casing into which the liquid is stored, the receptacle being in the form of a measuring-cup provided with suitable valve-controlled inlet and outlet ports hereinafter described.

40 B designates the casing of the outlet-valve connected to the threaded nipple C upon the measuring-cup, and D represents the inlet-valve casing, which is connected to and communicates with the casing B through a suitable connecting-pipe E.

45 F is a discharging device in the form of a spout, consisting of a tubular member G, fixed to the lower end of the valve-casing B, and a movable telescoping member H, mounted upon the stationary member for vertical reciprocation. The members are normally 50 separated by means of a coil-spring I, which abuts at its upper end against a flanged ring

J, secured to the stationary member, and at its lower end against the upper portion of the nozzle K.

55

L represents the outlet-valve, which bears normally against its seat M, and O is a valve-stem extending upwardly within the casing.

P represents a coil-spring encircling the valve-stem adapted to bear against a stop a upon the latter and the valve-casing and acting to normally hold the valve to its seat.

Extending within the stationary member of the discharge-spout is the stem b, carried by the valve just described.

65

c is a slot formed in the side of the upper tube or spout member, through which an arm d of a bell-crank lever e extends. This lever is pivoted at the junction of its arm to a bracket-arm a', secured to the spout. The 70 inwardly-extending lever-arm is connected in any suitable manner to the stem b, while the complementary arm f projects downwardly substantially parallel with the members of the spout and at some distance therefrom. Below the arm f is located a coin-receiving 75 support Q in the form of a shelf, the latter being substantially L-shaped in configuration and having one arm R slidingly engaging in any suitable manner the member b' of an angle-plate S, attached to the bracket-arm a'. 80

T represents the coin-chute, which extends from the entering-slot B' in the casing to the shelf just described and is so arranged and constructed as to deliver a coin upon said 85 shelf between the arm f of the bell-crank lever and the member G of the discharge-spout. Within the valve-casing D is arranged the valve U, provided with a stem V, connected through a yielding link g and a spring h to an arm i, extending outwardly from the angle-plate S. The yielding link comprises, essentially, a socket-piece j, in which the lower end of the valve-stem extends, and a spring k, which bears against the end of said stem, 90 the latter being secured to the link by means of a pin l, extending through a slot m in the stem, as plainly shown in Fig. 1. The spring h acts normally to hold the valve U away from its seat o, so as to allow the inlet to the measuring-cup to be normally open. The connection between this valve and the operating device of the mechanism, which in this case is 95

100 preferably the reciprocating member of the

discharge-spout, is the bell-crank lever u , pivoted upon the bracket-arm a' . One arm p of this lever projects past the yielding link and beneath the pin q , secured to the socket, 5 while the other arm r extends in a parallel direction with the discharge-spout and is held constantly in contact with said spout through the agency of the spring h .

After the coin has been inserted within the 10 machine and the device operated in the manner that will be hereinafter set forth the coin is automatically deposited into a box or coin-chamber X . The automatic means which I employ for this purpose is of the following 15 construction:

Y represents a roll journaled at its ends in the angle-plate S and a bracket-arm Z .

r' is a pin fixed upon the upper part of the roll adapted to engage the member R' of the 20 shelf, so that upon the movement of the roll in either direction the shelf will be actuated.

s designates a spring-actuated pin arranged within a recess t in the roll, the spring being fixed within said recess to prevent the pin 25 from being moved entirely out of the latter. The pin last described extends normally within the path of the tapered head C' upon the member H of the discharge-spout.

The liquid that is to be dispensed is supplied to the apparatus through the valve-controlled inlet-port, before referred to, in any suitable manner, necessarily under pressure when the source of supply is located beneath the machine. The liquid is free to pass normally 30 into the measuring-cup, and the air within the cup is forced out through the valve-controlled vent-tube a^2 . The measuring-receptacle consists, essentially, of the cup proper, b^2 , in which is arranged a piston-head c^2 .

d^2 designates a hollow piston-stem, which is provided with a head e^2 , swiveled within the piston, and extends outwardly from the cup through a stuffing-box h^2 and to and through a 45 threaded tubular bearing f^2 , supported upon the frame g^2 . At the upper end the piston-stem is provided with an operating handle or knob i^2 and is also threaded, as at j^2 , whereby the piston may be raised or lowered to determine 50 the quantity of liquid that is to be dispensed.

k^2 designates a valve for the hollow stem d^2 . l^2 is a tubular stem for this valve, extending within the hollow stem referred to, and is provided at the end thereof with a head m^2 . o^2 designates a spring interposed between this head and a shoulder p^2 upon the stem d^2 , the spring acting to maintain the valve normally 55 against its seat.

q^2 represents a threaded rod the upper end of which has a threaded engagement within the valve k^2 and its stem, while the lower end is connected to the stem of the valve L , the latter connection being preferably a lost-motion 60 connection of any well-known and suitable type, so as to insure the proper closing of both valves. The thread upon the rod q^2 is of the

same pitch as the thread upon the hollow piston-stem, and the valve k^2 is connected to the head e^2 by means of a suitable bolt e^3 . This bolt permits vertical movement, but prevents rotary movement, of the valve k^2 relatively to the head e^2 .

It will be seen from the above construction that the capacity of the measuring-cup may 75 be varied at will by simply turning the operating-handle and that the shifting of the piston to effect this variation will not in any way interfere with the action of the inlet-valves.

The parts of the mechanism having been 80 thus described, the operation of the machine is as follows: A coin is inserted within the entering-slot in the casing and is delivered by the chute upon the shelf in such manner as to form a coupling between the lever f and the 85 operating device. The operator then moves the section H upwardly until the tapering or inclined head thereon engages the lever-arm r , which actuates the valve U , closing the inlet-port to the receptacle. Upon further movement of the spout-section the head thereon forces in the pin s within the roller until the head passes by the latter, when the pin is released and engages beneath the head. Still further movement upward of the spout-section 90 causes the inclined head to bear against the coin, which forces out the lever-arm f , opening the outlet-valve and the valve k^2 . Air is thus enabled to enter through the piston-stem into the measuring-cup, and the fluid that 95 is to be dispensed passes down through the discharge-spout and into the glass or similar receptacle which is held beneath the same. After the contents of the receptacle have been 100 emptied the glass is withdrawn from beneath the spout and the latter is returned, by means of the coil-spring, to its normal position. The shoulder a^4 upon the head upon the downward movement of the spout-section engages the 105 pin s , which revolves the roller and forces the shelf from beneath the coin, allowing the latter to drop into the chamber or money-box before referred to. The shelf is automatically 110 returned to its normal position by means of a spring b^3 , which is connected to the roller and the angle-plate. The discharge of the coin 115 from the coin-pocket described allows the outlet-valve of the apparatus to automatically close, and the passage of the head out of engagement with the lever-arm r permits the 120 inlet-valve to be automatically opened. The fluid from the source of supply then enters the measuring-cup through the inlet-port, and the air in said cup is forced out through the air-vent a^2 , controlled by a float-valve a^5 . 125 In order that the operating device of the mechanism—viz., the reciprocative spout—may be readily actuated, I have provided a lip c^4 for the nozzle portion K , against which the glass is adapted to bear when raising the 130 spout. Also I have provided a strainer d^4 for the movable spout-section in order that the liquid that is dispensed may be free from impurities. The strainer referred to is in the

form of a tubular netting closed at one end, which is adapted to be inserted within the movable section and which is provided with a head e^4 , which has a threaded engagement 5 with the interior portion of the nozzle K.

What I claim as my invention is—

1. In a coin-controlled vending-machine, the combination of the reservoir provided with an inlet and an outlet port, a valve for each port, a controlling device for the outlet-valve, a reciprocative discharge-pipe for and communicating with the reservoir, a coin-chute adapted to deliver a coin into operative relation with the controlling device and discharge-pipe and operative mechanism intermediate the inlet-valve and said discharge-pipe, the parts being so arranged and connected as to be capable of operation substantially in the manner set forth.
- 20 2. In a coin-controlled vending-machine, the combination of the reservoir provided with an inlet-port normally open and an outlet-port normally closed, a valve for each port, a controlling device for the outlet-valve, a reciprocative discharge-spout for and communicating with the reservoir, a coin-chute adapted to deliver the coin into operative relation with the controlling device and into the path of the reciprocative spout, and means 25 controlled by the spout for operating the inlet-valve, the parts being so arranged that upon a partial reciprocation of the spout the valves will be set to close the supply and open the discharge, and upon the completion of the reciprocation of the spout the positions of the 30 valves will be reversed.
3. In a coin-controlled vending-machine, the combination of the reservoir provided with an inlet-port normally open and an outlet-port normally closed, a valve for each port, a controlling device for the outlet-valve, a reciprocative discharge-spout for and communicating with the reservoir, a coin-chute adapted to deliver the coin into operative relation with the controlling device and into the path of the reciprocative spout, means 40 controlled by the spout for operating the inlet-valve, the parts being so arranged and connected that upon the movement of the spout in one direction the valves will be set to close the supply and open the discharge, and means for automatically reciprocatting the spout to reset the valves in their initial position.
- 45 4. In a coin-controlled vending-machine, the combination with a reservoir provided with an inlet-port normally open and an outlet-port normally closed, a valve for each port, a discharge-spout for and communicating with the reservoir, a reciprocative section on the spout, a lever controlling the outlet-valve, a coin-chute adapted to deliver a coin against said lever and into the path of the spout-section and a controlling-lever for the inlet-valve 50 extending into the path of and adapted to be operated by said spout-section.

5. In a coin-controlled liquid-vending machine, the combination with the reservoir provided with an inlet-port normally open and an outlet-port normally closed, a valve for each port, a coin-chute leading to the coin-actuating mechanism, a movable support for the coin upon which the latter is adapted to be delivered from the chute, a coin-chamber beneath the support, the coin-actuating mechanism adapted upon the insertion of the coin to control the movement of the valves, an operating device controlling the operation of the coin-actuating mechanism adapted upon movement in one direction to reverse the normal positions of the valves, and means for automatically returning the operating device to reset the valves in their initial position and to deposit the coin within the coin-chamber.

6. In a coin-controlled vending-machine, the combination with a reservoir provided with an inlet-port normally open and an outlet-port normally closed, a valve for each port, a reciprocative discharge-spout for and communicating with the reservoir, an actuating mechanism for the valves adapted upon the insertion of the coin to be controlled by the spout, a movable support for the coin, a coin-chamber beneath the support, a coin-chute for delivering the coin upon the support, and actuating mechanism for the support intermediate the latter and the spout and adapted to be operated by said spout to deposit the coin within the coin-chamber.

7. In a coin-controlled apparatus, the combination with the receptacle provided with an inlet-port normally open, and an outlet-port normally closed, a valve for each port, a piston fitted within the receptacle, a hollow stem for the piston constituting an air-inlet for the receptacle, a spring-actuating valve for the stem, an operative connection between said spring-actuated valve and the valve in the inlet-port, an actuating mechanism for the valves controlling the ports, an operating device controlling, upon the insertion of the coin, the operation of the valve-actuating mechanism, said operating device being adapted when actuated to reverse the normal positions of the valves, and means for automatically actuating the operating device after its initial movement has been effected to reset the valves in their normal positions.

8. In a coin-controlled apparatus, the combination with the receptacle provided with an inlet-port normally open and an outlet-port normally closed, a valve for each port, a piston fitted within the receptacle, a threaded hollow stem swiveled to the piston and communicating with the interior of the receptacle, a threaded bearing engaging the stem, a spring-actuated valve for said stem, means for preventing the rotary movement of the stem independent of the spring-actuated valve, a connecting device secured to the valve in the outlet-port and having a threaded engagement with the stem-valve, an actuat-

ing mechanism for the valves controlling the ports, an operating device controlling, upon the insertion of the coin, the operation of the valve-actuating mechanism, said operating device being adapted when actuated to reverse the normal positions of the valves, and means for automatically actuating the operating device after its initial movement has

been effected to reset the valves in their normal positions.

In testimony whereof I affix my signature in presence of two witnesses.

ROBERT P. SCHILLING.
